UNITED STATES PATENT OFFICE

2,030,666

SCALE

Harold L. Walker, Brooklyn, N. Y., assignor to
The Jacobs Bros. Co. Inc., Brooklyn, N. Y., a
corporation of New York

Application May 11, 1932, Serial No. 610,559

4 Claims. (Cl. 265—69)

This invention relates to a structurally and functionally improved scale and aims to provide an article of this character which may readily be manufactured and set up to furnish an apparatus functioning over long periods of time with freedom from mechanical difficulty.

A further object of the invention is that of providing a scale in which weight indications will be accurately registered, despite variations in temperature.

A further object is that of providing a scale in which there will be little if any danger of the parts binding or becoming disarranged in such manner as would ordinarily require their being readjusted or reassembled.

With these and other objects in mind, reference is had to the attached sheet of drawing illustrating one practical embodiment of the invention, and in which:

Fig. 1 is a face view of a scale;

Fig. 2 is a sectional side view thereof;

Fig. 3 is a fragmentary partly sectional view of the beam and associated parts;

Fig. 4 is an enlarged view of the temperature-compensating structure and

Fig. 5 is a face view of the parts as shown in Fig. 4.

In these several views, the numeral 5 indicates a scale base upon which a platform 6 is supported to receive articles to be weighed. This platform is connected to a registering mechanism which, in the present embodiment of the invention, embraces a rockingly mounted pointer 7 which traverses the face of a dial 8, the latter being slotted or interrupted as, for example, at 9, so that the weight value registered may be observed from both sides of the scale, either through the openings 10 or 11 which are formed in the housing 12 encasing the registering mechanism. The platform 6 is mounted upon a rockingly supported beam 13 and the latter is connected in a manner herein-after described to a rack 14, the teeth of which mesh with a pinion 15 to the shaft of which the pointer 7 may be secured. It will also be noted that the pointer may be counter-balanced by a weight 16 and that a spring 17 may be provided for the purpose of resisting downward thrusts upon the platform 6.

In the illustrated embodiment, no attempt has been made to show the detailed adjustments which may be provided in connection with the spring and other mechanism of the scale. Also, while in the drawing a "fan type" scale has been illustrated, it will be apparent that this in-

vention might be embodied (as will hereinafter appear) in scales of various other types.

Referring primarily to the rack bar 14, it is well appreciated by those skilled in the art that considerable difficulty has been heretofore experienced, due to binding tendency between the teeth of the bar and the pinion. This has been caused usually, by the fact that the lower end of the rack bar has been capable of movements other than purely reciprocating. It will be apparent that, if in addition to thrusting or pulling the rack bar upwards and downwards, its lower end is swung, then a binding tendency is liable to be set up between the teeth of the parts aforementioned. Now, in order to overcome this difficulty, it will be observed, as in Figs. 2 and 3, that the end of the beam terminates in a curved surface 18 which is an arc of a circle having as its center the pivot 19 of the beam. It will thus be apparent that regardless of the position of the beam, that portion of the surface 18 which extends in a horizontal plane drawn from the beam pivots will be extending in a plane truly at right angles to such first named plane. Now, if the end of the rack bar is maintained in contact with the surface 18, it will be apparent that such rack bar will be guided so that its movements will be purely reciprocatory, thus overcoming the difficulties heretofore enumerated. With a view to assuring such contact, a stirrup 20 may have its upper end pivotally supported at the upper end of the surface 18, its lower end extending outwardly and bridging, for example, as at 21, the end of the bar 14, which is pivoted thereto. In this manner, the teeth of the rack 25 will always remain parallel with the teeth pinion. 30

Now, referring to the thermostatic structure, which forms part of the present invention, it will be observed that a pair of bi-metallic thermostatic strips 22 and 23 are secured to the beam in line 40 with the pivot 19. Secured to the outer ends of these strips are weights 24 and in mounting the strips, care should be taken that the metal which has the greatest co-efficient of expansion be normally disposed towards that side of the beam with which the spring is associated. Consequently, in cold weather the weights 24 will incline towards the left, as viewed in Figs. 2 and 3, and will compensate for the loss of weight which would ordinarily be indicated by the registering mechanism due to the temperature effect on the springs. Conversely, in the case of increasing temperature (i. e., higher than normal), the weights will incline to the right, as viewed in the figures in 45 50 55

question, thus again correcting any errors which would otherwise come into being.

Thus, among others, the several objects of the invention, as afore brought out, are achieved. It will, moreover, be appreciated that numerous changes in construction and rearrangements of the parts might be resorted to without departing from the spirit of the invention as defined by the claims.

10 Having described my invention, what I claim as new and desire to secure by Letters Patent, is:

1. A scale including a rockingly mounted beam, a thermostatic strip extending vertically in line with the beam pivots and secured to said beam and a weight secured to the upper end of said strip.

15 2. A scale including a rockingly mounted beam, a thermostatic strip extending vertically in line

with the beam pivots and secured to said beam and a weight secured to the lower end of said strip.

3. A scale including a rockingly mounted beam, a thermostatic strip extending vertically in line with the beam pivots and secured to said beam and weights secured to the upper and lower ends of said strip and disposed above and below the point of pivotal mounting of said beam.

4. A scale including a rockingly mounted beam, a thermal responsive member connected to said beam at right angles to the axis thereof, and a weight carried by said thermal responsive member and adapted to move toward or away from said beam and to either side of the point mounting thereof and in response to temperature changes. 15
